UNITED STATES PATENT OFFICE.

WILLIAM AITKEN, OF MUSWELL HILL, ENGLAND.

TELEPHONE DIVIDED MULTIPLE-SWITCHBOARD SYSTEM.

No. 927,470.

Specification of Letters Patent.

Patented July 13, 1909.

Application filed August 27, 1900. Serial No. 28,177.

To all whom it may concern:

Be it known that I, WILLIAM AITKEN, a citizen of Great Britain, residing at Muswell Hill, in the county of Middlesex, England, 5 have invented new and useful Improvements in Telephone Divided Multiple-Switchboard Systems, of which the following is a specification.

My invention relates to improvements in 10 telephone exchange systems of the central energy type, and has for its object the provision of a so-called divided multiple system. In a system of this type the subscribers are divided into two or more groups, all of the 15 subscribers of each group being connected to multiple jacks in a certain division of the switchboard, there being provided the same number of divisions in the central office as there are groups of subscribers.

20 Each subscriber has an answering terminal or jack and a signal therefor in each one of the divisions at the central office, and it is the particular object of this invention to provide means whereby the subscriber may call 25 any particular division at the central office without signaling the other divisions with which his line is connected. In the telephone directory each subscriber is designated by a 30 number or character which indicates with which division of the central office the desired subscriber is associated, to any other subscriber wishing to communicate. Therefore, a subscriber so actuates the substation 35 apparatus as to display a signal in the division of the switchboard upon which the multiple of the desired subscriber's line terminates. Certain advantages are gained over 40 systems of the straight multiple type, and these advantages assert themselves in a very 45 pronounced manner in large exchanges. For example, in any exchange of the two-division type the number of multiple jacks or terminals required will be half as great as in the one-division type, while the answering 50 terminals in the two-division type will be twice as great as in the one-division type. However, inasmuch as in an ordinary multiple switchboard the number of multiple terminals are largely in excess of the number of answering terminals it will be seen that the 55 number of terminals required in a two-division board is less than the number required in a single division board.

My invention has been worked out for two 55 and three-division switchboards and the cir-

cuits for the same are shown in the accompanying drawings, in which,

Figure 1 illustrates my invention as it would be used with a two-division switchboard; Fig. 2 illustrates my invention as it 60 would be used with a three-division switchboard, and Fig. 3 represents a modification of the two-division switchboard system shown in Fig. 1, by means of which cut-off contacts in the jacks may be used instead of 65 cut-off relays.

Referring to Fig. 1, the line wires A and B extend from the central office to the substation C, this station being provided with the usual common battery substation apparatus, 70 consisting in the signal d , transmitter d' , receiver y , repeating coil w w' , condenser d^2 , and switch-hook d^3 . In addition to these the substation is provided with keys A' and B' , the depression of key A' being adapted to 75 sever the line conductor A from the substation telephone apparatus, and connect it with earth, and the depression of the key B' being adapted to sever the line conductor B from its connection with the substation apparatus and to connect it with earth. At 80 the central office the limbs of the telephone line terminate, in one of the divisions, in multiple terminals shown at A^2 , and in answering terminals having two contacts a^2 and b^2 , and in the other division, in the answering jack B^2 , having the line contacts a^3 and b^3 . Each of these jacks is also provided with a third, or sleeve contact isolated from the 85 limbs of the telephone line and adapted to 90 serve as a test contact in the multiple section. Line terminal A is connected to the armature h' of cut-off relay h , and thence through the normal contact h^2 of this cut-off relay, through the coil of line relay R to the 95 live pole of battery i . Line terminal B is connected to the spring h^3 of cut-off relay h and thence through the normal contact h^4 of such relay through the coil of line relay R^4 to the live pole of the battery i . The armature 100 R' of the relay R is connected to the ground side of the battery i and is adapted when actuated to make connection with the normally open contact R^2 which is permanently connected with the line conductor A. Likewise, the armature R^5 of relay R^4 is connected with earth and is adapted by its actuation to make connection with the normally open contact R^6 which is permanently connected 105 to the line conductor B. The cut-off relay h 110

has its coil connected between the sleeve contacts of the line jacks and the earthed pole of battery i and is adapted by its actuation to sever the connection between the line 5 terminals and the line relays R and R' . In parallel with these line relays are the line signals J and J' , one being located in each of the two divisions of the switchboard, preferably just above or below the answering terminals 10 in each division.

The cord or connecting circuit shown herewith extends in two talking strands between the tips q^3 and q^6 , and the rings q^2 and q^5 of the two connecting plugs, the tip strands being 15 carried through the windings of the repeating coil and connected to the live pole of the battery i , and the ring strands being carried through the coils of relays o and o' and the windings of a repeating coil and connected 20 with the ground pole of the battery i . The sleeve contacts q^1 and q^4 are normally connected through signals p and p' , and x and x' with the live pole of the battery i , such signals being adapted to be shunted respectively by the resistance x and x' by a corresponding actuation of relays o and o' .

The operation of the circuit thus described is as follows: The subscriber desiring communication with another subscriber first 30 ascertains in which division of the switchboard the desired subscriber's line is multipled. Assuming him to have found this division to be that represented by the signal J , the subscriber presses his button A' , which 35 connects the line conductor A with earth. Current now flows from the battery i through line relay R , normal contacts h^2 and h' of cut-off relay h and over the line conductor A to earth. This current actuates relay R 40 and connects the earth terminal of battery with the line conductor A through contacts R' and R^2 of relay R . Current in this path now locks the relay R in actuated position and maintains the actuation of the signal J 45 whether or not the key A' at the substation is actuated. The central operator before whom the signal J appears inserts her plug q into the jack indicated by the signal and thereby closes a path for current from the 50 live pole of battery i through the resistance x' , signal p and resistance x , in parallel, to the sleeve of the plug q , sleeve of the jack c^2 , coil of the cut-off relay h to the ground pole of battery i . Current in this path actuates 55 the relay h , and severs the circuit of line relay R and signal J , such that the signal will now be effaced. Energizing current now flows from the live pole of the battery i over the tip strand of the cord circuit through 60 the tip contact a^2 of the answering jack over the limb A of the telephone line through the apparatus of the subscriber's set, which is now in talking condition, back over the limb of the telephone line B , jack spring b^2 , 65 ring conductor of the cord circuit q^2 through

coil of relay o , and back to the ground pole of battery i . This actuates the relay o and maintains the signal p in an inoperative condition during the conversation. The operator having obtained the desired number 70 inserts her plug q^7 in the multiple jack of the desired line, thereby displaying her supervisory signal p^3 by completing a path through the sleeve of her plug q^7 and the cut-off relay of the desired line, such signal 75 remaining actuated until the desired subscriber answers his call, at which time the relay o^3 will be energized to place a shunt about the signal p^3 , and thereby efface it.

Referring to Fig. 2, the line conductors A 80 and B extend to the substation, the usual apparatus of which is here designated simply by the signaling bell d . This substation is also provided with a key A' adapted by its actuation to disconnect the line conductor A from 85 the usual telephone apparatus of the substation and connect it with earth. Likewise, the push button B' is adapted by its actuation to disconnect the line conductor B from its connection with the usual telephone apparatus and connect it with earth. This station is also provided with a push button C' adapted by its actuation to engage both push button A' and push button B' and thereby 90 simultaneously disengage both of the line 95 terminals A and B from the usual substation apparatus and connect both line terminals with earth. At the central office this system is provided with three divisions, this particular line being provided with answering and 100 multiple terminals in one division, and with answering terminals in each of the other two divisions, these jacks being respectively provided with line terminals a and b , a' and b' , a^2 and b^2 , and with sleeve or test terminals c , c' and c^2 . Line conductor A is connected with an armature h' of cut-off relay h and through normal contact h^2 thereof connects with the coil of line relay k , and thence to the live pole of battery i , while the line conductor 105 B is similarly connected with the armature h^3 of cut-off relay h , and thence through the coil of line relay k^6 with the live pole of battery i' . Relay k has the armature k^2 adapted by its 110 actuation to connect the ground pole of battery i' with the line conductor A and also has the armature k^3 permanently connected with the coil of relay k^6 and normally connected through contact k^4 through signal j' with the live pole of battery i' . This armature k^3 is 115 adapted by its actuation to make connection with the contact k^5 which leads through the signal j^2 to a corresponding normally open contact k^{11} of relay k^6 . The armature k^6 of relay k^6 is permanently connected with the live pole of battery and normally connected through contact k^{10} and the signal j with the coil of relay k and the normally closed contact k^2 of cut-off relay h . Relay k^6 also has 120 the normally open contacts k^7 and k^8 adapted 125 through contact k^{10} and the signal j with the coil of relay k and the normally closed contact k^2 of cut-off relay h . Relay k^6 also has the normally open contacts k^7 and k^8 adapted 130

by their actuation to connect the line conductor B with the ground pole of battery i' . In the operation of the system thus described we will first assume the subscriber to desire the division of the switchboard called by pressing his button A'. This closes a path from earth over the line conductor A through the normally closed contacts h' and h^2 of the cut-off relay h and the coil of line relay k to the live pole of the battery i' . This actuates relay k connecting the ground pole of battery i' through contacts k' and k^2 directly on the line conductor A, thus locking the relay k and completing the circuit of the signal J from ground through the contacts k' and k^2 of relay k , contacts h' and h^2 of relay h , the signal J, contacts k^{10} and k^9 of relay k^6 , back to the live pole of the battery i' . The actuation of relay k connects its armature k^3 with the contact k^5 , but this does not close the circuit of signal J^2 because its circuit is open at contacts k^{11} and k^9 of relay k^6 . Upon the insertion of the plug the cut-off relay h is actuated and the circuit of relay k and of the signal J is severed at the contacts h' and h^2 of the cut-off relay. Supposing the subscriber to desire the division signaled by the actuation of key B', current will flow from earth over the conductor B, through the normal contacts h^3 and h^4 of the cut-off relay h and actuate the line relay k^6 . The actuation of this relay closes the contacts k^7 and k^8 and connects the ground pole of battery through the contacts h^3 and h^4 of relay h , conductor l , through contacts k^3 and k^4 of relay k , through the signal J' to live pole of battery. This displays the signal J' and locks the relay k^6 in actuated condition. The closing of contacts k^9 and k^{11} of relay k^6 does not, however, display signal J^2 , because the circuit of that signal is open at contacts k^3 and k^5 of relay k . Again, suppose the subscriber to desire to signal the third division he will then depress his key C', which will, by the nature of its construction, actuate both keys A' and B', as before described. The simultaneous actuation of keys A' and B' will actuate line relays k and k^6 simultaneously over the same circuits as when the keys A' and B' are individually actuated. The actuation of contacts k' and k^2 of relay k will place ground upon the line conductor A, and thereby lock relay k in actuated position, and the actuation of contacts k^7 and k^8 of relay k^6 will place ground upon the line conductor B, and thereby lock relay k^6 in its actuated condition. Signals J and J' will not now be actuated, however, the circuit of signal J being interrupted by the opening of contacts k^{10} and k^9 of relay k^6 , and the circuit of signal J' being opened at contacts k^3 and k^4 of relay k . Contacts k^3 and k^5 of relay k and contacts k^9 and k^{11} of relay k^6 now being closed the circuit of signal J^2 will be completed from the ground pole of battery through contacts k^3

and k^5 , the signal J^2 , contacts k^{11} and k^9 to the live pole of battery. Upon the insertion of the answering plug in the jack designated by the display of signal J^2 the cut-off relay h will be actuated and the line signal effaced by the deenergization of the two line relays.

In Fig. 3 is shown a circuit which operates on substantially the principle of Fig. 1, this circuit being provided, however, with cut-off contacts in the jacks instead of the cut-off relay shown in Fig. 1. The line conductors A and B are carried serially through the contacts of the multiple and answering jacks of the terminals of one division, and through the answering jack in the terminal at the other division of the switchboard. When, for example, the subscriber presses his button which grounds the line terminal A current flows through the series contacts a^1 , a^2 and a^3 , and then through the coil of the line relay k . The actuation of the line relay places ground upon line conductor a in advance of the first series contact of the jacks, such that the line relay k will be locked in actuated position and the signal J will thereby be displayed until the plug is inserted in the jack, at which time the series contacts will be opened and the circuit of the line relay and the signal J will be opened. The line relay then falling back to sever the ground connection with the line, the actuation of the button which places ground on the conductor B will similarly actuate line relay k^6 and display the signal J.

My invention is here shown in connection with a specific form of cord circuit and specific forms of line circuits, but it is to be understood that I do not wish to be unduly limited thereto, any other desirable form of cord circuit and many variations in the shown and described line circuits being quite possible without in any way departing from the spirit or scope of my invention.

Having now particularly described and ascertained the nature of my said invention and in what manner the same is to be performed, I declare that what I claim is:

1. In a telephone system, the combination with a telephone line, of a central source of current with which the line connects, said source supplying the transmitter current for said line during conversation a plurality of signals upon the line located upon different divisions of the switchboard, switches at the substation one for each signal and adapted to individually and selectively operate the same, and means for maintaining any of said signals in operated condition after the release of the switches, substantially as described.

2. In a telephone system, the combination with a telephone line, of a central source of current associated therewith for both signaling and talking purposes, a signal therefor, a switch at the substation to operate said sig-

nal from said source and a circuit for said signal closed in the operation of the same to maintain the same actuated after the release of the switch, substantially as described.

5 3. In a telephone system, the combination with a telephone line, of a central source of current with which the line is connected to furnish current for its transmitter during conversation, three signals for the line located upon the different divisions of the switchboard, means at the substation for individually and selectively controlling the operation of said signals, and a cut-off relay energized when a connection is established 10 with the line to render said signals inoperative, substantially as described.

4. In a telephone system, the combination with a telephone line, a plurality of line relays for the line, a plurality of signals for the line greater in number than said relays, means to actuate said relays from the subscribers' stations so as to selectively operate said signals, and means to render said signals inoperative when a connection is established 20 with the line, substantially as described.

5. In a telephone system, the combination with a telephone line, of a central source of current with which the line connects to operate its transmitter, a plurality of signals for the line also adapted to be operated by said source and located upon different divisions of a divided central switchboard, switches at the substation one for each said signal and adapted to individually and selectively operate the same, and locking circuits for said signals to maintain any of the same operated after the release of their respective switches at the substation, substantially as described.

6. In a telephone system, the combination 40 with a telephone line, of a central source of current with which the line is connected to furnish energy for its transmitter during conversation, a line signal for the line on each division of a divided central switchboard, means at the substation for selectively operating any of said signals by current from said source, switches at the central office for maintaining the proper signals operated after the release of said switches, and means to 45 render said signals inoperative when connection is established with a line at any of the divisions of the switchboard, substantially as described.

7. In a telephone system, the combination 55 with a telephone line, of line relays, one associated with each limb of the telephone line, means at the substation for jointly or individually completing the circuit of said line relays, and three signals selectively displayed 60 by the selective actuation of said relays, substantially as described.

8. In a telephone system, the combination 65 with a telephone line, of a plurality of signals for said line located upon the different divisions of a divided central switchboard, line

relays to control said signals, a central source of current having one pole normally connected with both limbs of said line for the actuation of said line relays and adapted to be connected with said line through a different 70 path for the energization of its transmitter during conversation, a plurality of switches at the substation for the selective operation of said relays, and means at the substation for selectively operating any of said signals 75 by the selective operation of said relays, substantially as described.

9. In a telephone system, the combination with a telephone line, of a plurality of signals for said line located upon the different divisions of a divided central switchboard, a central source of current for the energization of the substation transmitters, a plurality of line relays normally connected with said line for the actuation of said signals, a plurality of 80 buttons at the substation adapted by their selective operation to individually actuate said relays, and means whereby the individual actuation of said relays will selectively control said signals, substantially as de 85 scribed.

10. In a telephone system, the combination with a telephone line, of line relays having their coils normally connected, one in each limb of said telephone line, a cut-off relay for disconnecting the coils of said relays during conversation, a central source of current having one of its poles connected directly with the coil of each of said relays, means at the substation for selectively completing the circuit of said source through said 95 relays, and signals at the central office selectively controlled by the selective actuation of said relays, substantially as described.

11. In a telephone system, the combination 105 with a telephone line, of a plurality of signals for said line located upon the different divisions of a divided central switchboard, a central source of current normally connected with said line for the actuation of 110 said signals, and adapted to be connected with said line through a different path for the energization of its transmitter during conversation, and means for individually and selectively completing the circuit of any 115 of said signals from the substation of said line, substantially as described.

12. In a telephone system, the combination 120 with a telephone line, of line relays having their coils normally connected, one in each limb of said telephone line, a central source of current having one of its poles connected with the coil of each of said relays, means at the substation for selectively or collectively completing the circuit of said source 125 through said relays, and signals at the central office selectively controlled by the selective or collective actuation of said relays, substantially as described.

13. In a telephone system, the combina- 130

- tion with a telephone line, of a plurality of signals for said line located upon the different divisions of a divided central switchboard, a central source of current normally connected with said line for the actuation of said signals and adapted to be connected with said line through a different path for the energization of its transmitter during conversation, of means at the substation of said line for selectively displaying any of said signals by the temporary closing of a key, and means at the central office whereby said signal will be maintained actuated after said key has again been opened, and a cut-off relay adapted to be actuated when a connection is made with said line to again suppress said signal, substantially as described.
14. In a telephone system, the combination with a telephone line, of a cord circuit adapted to be connected therewith, a plurality of signals associated with the line and located upon the different divisions of a divided central switchboard, a central source of current for said line adapted for the actuation of said signals and to furnish current for the transmitter of said line, a line relay in each limb of the line, means whereby either of said relays may be selectively actuated from the substation of said line to selectively actuate the signals, and further means for suppressing said signal when said cord circuit is connected with the line, substantially as described.
15. In a telephone system, the combination with a telephone line, of a plurality of signals greater than two located upon different divisions of a divided central switchboard, a source of current at the central office and means at the substation for causing current from said source to selectively actuate said signals, substantially as described.
16. In testimony whereof I have signed my name to this specification in the presence of two subscribing witnesses.
